MEASURING PUMP

Samuel L. Adelson, Chicago, Ill., assignor to Infilco Incorporated, a corporation of Delaware

Application May 9, 1940, Serial No. 334,145

15 Claims. (Cl. 103—44)

This invention relates to measuring pumps. It is particularly useful for measuring and pumping a fluid which tends to attack or corrode metal. The invention will be specifically described as used for feeding ferric chloride solution into sewage for purification of the sewage. The field of application is considerably broader than that so described. The specific terms hereinafter used are meant to illustrate but not to limit the invention.

Ferric chloride solution is an efficient and economical coagulant for impurities contained in sewage. Its advantages have been known theoretically for considerable time, but its practical application has met with difficulties caused in part by its inherent corrosiveness and in part by shortcomings of apparatus heretofore proposed for pumping or measuring corrosive, or fluids of any kind.

Liquid pumps known to the art are of the piston or plunger or diaphragm type. An inherent problem of pistons is that of liquid slippage. It is one of the essentials of its construction that a mechanical piston has sliding fit in a surrounding cylinder; and that involves the absence of a perfect seal. Substantially the same thing is true of a plunger. A diaphragm prevents liquid slippage; but as the edge of a diaphragm essentially must be sealed and fastened to a housing, close limits are set to the movement of the diaphragm. The diaphragm material as used in pumps known to the art must be strong and flexible at the same time; such requirements are somewhat conflicting. Motion transmitted from the center of a diaphragm to the outer parts thereof as generally done in the prior art, cannot be precise, especially where the suction lift or discharge head or both are subject to variation. Piston or plunger pumps are better in that respect; but pistons and plungers, and the cylinders thereof, cannot be economically or efficiently constructed from rubber or other materials required by certain fluids, and they are unsuitable wherever a perfect or nearly perfect liquid seal is required to prevent inaccuracy due to slippage, to protect necessary metal parts from aggressive fluids, or to avoid the escape of fluid for any other reason.

It is a general object of my invention to provide a pump wherein a body of liquid is reciprocated by a mechanical piston and in turn reciprocates a diaphragm which is interposed between the liquid piston and the fluid to be pumped.

It is a particular object to provide simple and

efficient means for controlling the liquid piston or for centering the same with respect to the mechanical piston and the diaphragm.

Another general object of my invention is to provide a measuring pump adapted to perform the service outlined and being free from the limitations and shortcomings of prior devices.

Another important object is to provide a measuring pump wherein the rate of pumpage can be predetermined and maintained constant regardless of variations in suction lift or discharge head or both.

Another important object is to provide a diaphragm pump, the diaphragm of which is flexible and may be made from impervious material of little mechanical strength, but yet efficiently protected against distortion and stresses affecting the rate of pumpage or raising the danger of diaphragm failure.

Another object is to provide a pump comprising automatic means for controlling or correcting the position of the pumping member during operation thereof.

Still another object is to provide a pump or feeder that can be readily adjusted while in operation.

Still other objects will appear on consideration of the following description and of the appended drawings, wherein

Fig. 1 shows a preferred embodiment of my invention in side elevation, the main operating parts being shown in section;

Fig. 2 is a diagram showing the complete hydraulic system of the invention, simplified by omitting certain auxiliary mechanical parts and showing other parts in purely diagrammatical form;

Figs. 3 to 6 are simplified diagrams of certain phases of the normal operation of the device;

Fig. 7 is a simplified diagram showing a phase of irregular operation of the device and thus illustrating the function of certain steps in regular operation thereof;

Figs. 8 and 9 are simplified diagrams of certain phases of automatic control in the regular operation of the device; and

Fig. 10 is a simplified diagram of a prior art device illustrating certain functions and advantages of the present device.

In the drawings numeral 10 designates a constant speed electric motor actuating the speed reducer 11 to drive crank 12 which in turn reciprocates piston rod 14 by means of link 13, additional compound linkage being provided as hereinafter described. Piston 15 has its wrist

pin pivotally secured to piston rod 14 and slides in the bore of cylinder 16. This cylinder is installed in upright position with its upper end open to the atmosphere through a recess 17 formed in the cover plate or splash guard 18 of the cylinder; and piston rod 14 may pass through recess 17, no liquid seal being required for this rod. It will be seen that the front of piston 15 and the inner wall of cylinder 16 therebelow form an expandable chamber which may be designated as primary pump chamber or piston chamber 19. This chamber is spaced from a diaphragm chamber or secondary pump chamber 21 by an intermediate transmission chamber 20. The transmission chamber is confined by a wall of generally cylindrical shape, with horizontal axis. The wall of the transmission chamber has a flattened portion in the upper part of the outer side thereof. The vertical cylinder 16 of piston 15 is joined to such flat portion by suitable flanges 22. The primary pump chamber 19 communicates with transmission chamber 20 through a cylindrical bore in the wall of the latter, in the center of flange 22. Diaphragm chamber 21 is substantially bell shaped and its wall may merge into that of transmission chamber 20, allowing free communication between the two chambers. The transmission chamber may be supported as at 23 and may directly or indirectly support the other chambers referred to as well as the motor and other auxiliary parts of the apparatus. The walls of cylinder 16, transmission chamber 20 and diaphragm chamber 21 can be made of cast iron or the like.

In the interior of transmission chamber 20 there is a partition extending across the axis of the chamber formed by an imperforate, rigid diaphragm 24 having a horizontal cylindrical passageway 25 formed therein. The axis of passageway 25 coincides with that of transmission and diaphragm chambers 20 and 21. Diaphragm chamber 21 is closed and sealed at the far end thereof spaced from transmission chamber 20 by a thin and flexible soft rubber diaphragm 26. An elongated rod 27 which may be made of brass has one end thereof supported by and rigidly secured to the center of diaphragm 26 by clamp members 28, the opposite end of the rod being slidably inserted in a guide box 30 formed in the end wall 29 of transmission chamber 20 so that the rod extends through passageway 25 and its axis coincides with that of the passageway. The guide box 30 may be of the antifriction type, no liquid seal being required at this point but a thimble 31 being sealed to the outside of wall 29 around box 30 so as to catch whatever transmission liquid may bleed through the guide box 30. Rod 27 is not an actuating member for the diaphragm 26 but a carrier of control parts to be described presently, which control parts may be made of brass, the same as the rod; the rod responds to movements of the diaphragm imparted by the transmission liquid and the general construction is such that the rod and parts associated therewith may oppose no appreciable resistance to the movement of the diaphragm. For this reason rod 27 is made very thin and light so that diaphragm 26 is substantially free from load or stresses which might otherwise be imparted thereto by the weight of the rod and associated parts, which loads or stresses might tend to distort the diaphragm or otherwise to affect the operation thereof. In cases where the diaphragm has to be particularly sensitive and thin an additional

support for rod 27 may be provided spaced from guide box 30 and in form similar to the same so as to completely eliminate gravitational stresses from diaphragm 26.

The control parts mentioned comprise sleeve 32 which is slidably disposed on rod 27 and which extends through passageway 25, an annular space being left between the inner wall of the passageway and the outer wall of the sleeve, for the transfer of transmission liquid. The sleeve has valve disks 33 and 34 rigidly secured to its end portions on opposite sides of passage 25. Partition 24 in which the passage is formed has valve seats 35 and 36 formed therein at the ends of passage 25 facing valve disks 33 and 34 respectively. Sleeve 32 with the two valve disks thereon is yieldably positioned on rod 27 by small and feeble compression springs 37 and 38 which springs extend along rod 27 from abutments 39 and 40 projecting from the rod. It will be seen that whenever valve 33 or 34 is seated on the respective seat 35 or 36, the passage 25 is sealed and transmission chamber 20 hydraulically separated into two compartments forming extensions of the primary pump chamber 19 and of the secondary pump chamber 21 respectively. Normally, however, the passage 25 is free and unobstructed and in such condition the whole space of pump chamber 19, transmission chamber 20 and diaphragm chamber 21 can be considered a single chamber or compartment, and the transmission fluid with which the pump is provided can be considered as a single body of fluid filling the whole of such single chamber or compartment.

A storage chamber 41 for transmission liquid is provided adjacent cylinder 16 and downwardly extending from adjacent the top thereof to a point adjacent transmission chamber 20. The upper portion of the cylinder 16 and the storage chamber 41 are connected by suitable overflow means, such as lowering the common wall between the two, as shown, whereby transmission fluid which leaks by piston 15 from chamber 19 is collected in the storage chamber 41. At the bottom of this storage chamber there are two compensating valves 42 and 43 which are normally held closed by compression springs of suitable strength. Either of the two compensating valves 42 and 43 when unseated allows flow of transmission liquid from or to transmission chamber 20. Both compensating valves communicate with that part of transmission chamber 20 which forms an extension of piston chamber 19 when passage 25 is closed, so that the compensating valve 42 or 43 can be unseated against the action of the spring thereof, by moving piston 15 downwardly or upwardly while passage 25 is closed.

Diaphragm 26 separates the secondary pump chamber 21 from the ultimate pump chamber 44 for ferric chloride. The latter pump chamber is preferably made from hard rubber. It communicates with a supply of ferric chloride solution through the soft rubber suction hose 45 including check valve 46 and it communicates with the sewage conduit through soft rubber discharge hose 47 including check valve 48. Any suitable form of check valve can be used; the two check valves can be combined in a single casing and other modifications applied as is well understood by persons skilled in the art.

Motor link 13 and the piston rod 14 are pivotally secured together to form a compound system or toggle with two rate setting rods one of 73 which is shown at 49, the other being parallel

thereto and each of said rate setting rods 49 having one end thereof pivoted to the pin which connects members 13 and 14 and the other to one side of a rate setting yoke 50. This yoke is slidably supported from cylinder 16 by means including bracket 51, screw 52 turnably held by said bracket, and nut 53 threadedly engaging screw 52 and rigidly secured to yoke 50. Longitudinal adjustment of nut 53 on screw 52 can be effected by turning the screw by means of knob 54. The position of nut 53 on screw 52 controls that of yoke 50 and that in turn controls the length of the stroke of piston 15 through the medium of toggle 49, 13.

In order to complete the hydraulic system in accordance with this invention, transmission liquid TL must be put in chambers 19, 20, and 21 and there must be a supply 60 of ferric chloride $FeCl_3$ at the intake of the suction hose 45 and a receptacle or conduit 61 for sewage S to be dosed or otherwise for disposing the ferric chloride therein at the end of discharge hose 47, as diagrammatically shown in Fig. 2. The pump is self-priming; that is, when the check valves are in good condition and the suction hose is not collapsible then the apparatus at the start of the operation pumps the air out of chamber 44 gradually raising the ferric chloride from supply 60.

Important phases of the normal operation of the device are shown in Figs. 3 to 6 in each of which the neutral or central position of piston 15 is indicated at 15A, that of diaphragm 26 at 26A, and that of valve disks 33 and 34 at 33A and 34A respectively. It will be seen that piston 15 is caused to reciprocate in cylinder 16 thereby shifting transmission liquid in and through the chambers 19, 20 and 21 which shifting movement of the liquid in turn produces a pulsating movement of diaphragm 26 between the two bodies of liquid, the transmission liquid on one side and ferric chloride on the other. In effect the two bodies of liquid act as one and the liquid pressure on both sides of diaphragm 26 is uniform at all times. The unweighted and flexible diaphragm can freely move with the liquid within the limits determined by the diaphragm construction, material and installation. The peripheral portion of the diaphragm, being rigidly secured to the stationary walls of chambers 21 and 44 is at rest. The central portion of the diaphragm reciprocates horizontally between outer limits the precise spacing of which is a function of (a) the length of stroke of the mechanical piston 15 and (b) the slip, if any, of transmission liquid past the mechanical piston. The volume of transmission fluid displaced from or into chamber 19 by a stroke of the mechanical piston 15 equals the volume of the zone of pulsation of diaphragm 26 in chamber 21, the storage chamber 41 being sealed from transmission chamber 20 by valves 42 and 43 and the transmission fluid being a liquid and therefore not compressible. The volume of the zone of pulsation of diaphragm 26 in turn equals the volumetric amount of ferric chloride raised and displaced from source 60 towards discharge 61.

As the diaphragm 26 pulsates the central part of the diaphragm moves as described and shifts rod 27 with sleeve 32 back and forth through 70 passage 25 so that valve disks 33 and 34 alternately approach the respective seats 35 and 36. The spacing of disks 33 and 34 from one another, from diaphragm 26 and from seats 35 and 36 is made such that in normal operation a full stroke 75

of piston 15, as reflected by the shifting of rod 27, fails to seat either of the two disks on the respective seat. The springs 37 and 38 operate to maintain such appropriate spacing. They prevent the sleeve 32 from shifting along rod 27 incident to acceleration or deceleration at the beginning or end of any excursion of the rod and thus they prevent the disks 33 and 34 from approaching their respective seats beyond the point to which they are carried by rod 27. Accordingly transmission liquid unobstructedly communicates through passage 25 and the liquid piston is operative during such normal operation.

Fig. 3 shows the device at the start of a normal pump stroke or cycle of operation. Piston 15 is in raised position at 15B, diaphragm 26 is flexed to the left as shown at 26B, and valve disks 33 and 34 are at 33B and 34B, allowing communication through passage 25. The check valves 46 and 48 are closed. The level of ferric chloride in supply tank 60 is at 60B.

Fig. 4 shows the device shortly after the start of the downward stroke of mechanical piston 15 in normal operation. Piston 15 has moved a short distance downwardly from 15B. Diaphragm 26 and valve disks 33 and 34 have moved a little toward the right. Suction check valve 46 remains closed but discharge check valve 48 has opened under the pressure of fluid displaced by diaphragm 26 on its travel towards the right. Ferric chloride is being discharged into receptacle 61.

Fig. 5 shows the device at the end of such downward stroke and at the start of the subsequent upward stroke of mechanical piston 15. Piston 15 has moved further down from 15B to 15C. The diaphragm and valve disks have further moved to the right to position 26C, 33C, and 34C respectively. Suction check valve 46 still remains closed. Discharge check valve 48 is still open but the discharge of ferric chloride has ceased as the forward movement of piston 15 has reached zero value.

Fig. 6 shows the device shortly after the start of the upward stroke of mechanical piston 15. Piston 15 is somewhat above point 15C. The diaphragm and valve disks have started on their way back to the left from 26C, 33C and 34C respectively. The discharge check valve 48 has closed under the suction of the receding diaphragm and the suction check valve 46 has opened under the same influence. Ferric chloride is being lifted from source 60 and the solution level drops below 60B.

At the end of the upward stroke piston 15, diaphragm 26 and valve disks 33 and 34 return to their respective "B" positions; suction check valve 46 closes and discharge check valve 48 still remains closed. Thus the original position of Fig. 3 is restored; an operating cycle has been completed and a new cycle is about to start.

Operation as shown in Figs. 3 to 6 could theoretically continue indefinitely if there was no slip of transmission liquid past the mechanical piston 15. However, in practice some liquid slippage will necessarily occur either on the forward or on the backward stroke or on both. If there is slippage on both strokes it theoretically could cancel out but practically there will be some net or excess slippage in either direction.

The net amount and direction of slippage depends on various structural factors determined by slight and uncontrollable irregularities in the construction and installation of the machine, especially on the fitting between the skirt of pis-

ton 15 and the bore of cylinder 16 at each point of contact, the area of the skirt, the magnitude of suction head and the pressure head and the like.

Some of those structural factors may be subject to variations of even slighter magnitude as operating conditions vary from time to time. Aside from varying loads on the pressure or suction strokes there are other factors which possibly may so affect the phenomenon of liquid slippage, including for instance the operating temperature, the contraction and expansion of the piston and cylinder and the the change of viscosity of the transmission liquid.

A control of such constant or changing factors, or of the liquid slippage itself, is necessary for reasons which appear from a consideration of Fig. 7. This figure assumes a tendency of the transmission liquid to escape on the downstroke of piston 15 rather than on the upstroke. Normal pulsation of diaphragm 26 is between the marks 26M and 26N which are equally spaced from the centerline 26A. Under the conditions assumed, however, there would be an unbalanced tendency of the diaphragm pulsation to be displaced towards the left as the amount of transmission liquid in chambers 19, 20 and 21 would be reduced by uncompensated slippage away from chamber 19 on each downstroke. After some time the diaphragm would pulsate between the marks 26P and 26Q. Mark 26P would tend to come close to the wall of the diaphragm chamber and even to pass beyond the same whereupon the device would become inaccurate because diaphragm 26 would abut against the wall of its chamber; it would be partly removed from the action of the transmission liquid and the remaining part excessively bulged and stressed as shown at 26O. When this extreme condition of pulsation described has been reached, as indicated by the mark 26O, adjustment of the length of the pump stroke, by means of knob 54, would no longer accurately adjust the amount of pumpage. Such extreme pulsation and distortion of the diaphragm 26, would ultimately tend to burst the diaphragm, rendering the pump inoperative.

Control or compensation of the liquid slippage cannot be achieved by the construction or operation of the piston or cylinder itself. However, it can be controlled by other means, such as shutoff valves 33 and 34 and compensating valves 42 and 43. The control operates in the manner shown in Figs. 8 and 9.

Fig. 8 again assumes a net or excess slippage of transmission liquid on the downstroke of piston 15. As explained before, accumulated slippage tends to displace the diaphragm pulsation in direction from an original line 26R—26S to the line 34R—34S to the line 34T—34U. In the place the reciprocation of valve disk 34 from the line 34—34S to the line 34T—34U. In the position 34T, near the limit of a suction stroke, the valve disk 34 approaching seat 35 leaves only a very small annular slot at the end of passage 25. This restricted opening or slot creates an appreciable pressure differential in the flow or displacement of transmission liquid, the amount of the differential being a function of the pressure then acting on the area of this restricted opening, the size of the opening, and other factors well known to the art. Successive suction strokes would tend to bring the terminal suction position of disk 34 still farther to the left beyond point 34T. The differential at pas-

sage 25 would become successively greater on each suction stroke. However, near the limit of one suction stroke, this differential becomes great enough to overcome the slight resistance of spring 37. Thereupon disk 34 seats on valve seat 36 with snap action, shifting the sleeve 32 further to the left over the very small distance remaining and promptly sealing the passage 25.

This obviously occurs at a moment when pressure is still being applied by the mechanical piston, that is (Fig. 9), before the terminal position 15X of the suction stroke is reached and before the diaphragm 26 and control valve 34 have assumed the terminal "X" positions they would ultimately reach. Due to the rapid action of the substantially uncompensated mechanism of valve 34, 35, as described, the seating of the valve from 34Y to 34Z is both initiated and completed before the end of the suction stroke of piston 15. As this suction stroke is being completed from 15Y to 15X after the closing of the valve 34, a vacuum is created in the combined chambers 19, 20 sufficient to overcome the pressure of the spring of the compensating valve 43, whereupon the compensating valve 43, affording communication with and from storage chamber 41 is opened against the pressure of the spring of this compensating valve, admitting a sufficient amount of transmission liquid from storage chamber 41 into transmission chamber 20 to practically offset the loss of transmission liquid incurred by slippage on previous pressure strokes.

Accordingly the next pressure stroke brings the righthand limit of diaphragm pulsation back to a position identical with or approximating the initial one, 26S. The next suction stroke is from that position to a position at or near the original lefthand limit 26R. Subsequent strokes again will tend to displace the pulsations to the left. At some time there will be the same compensating action as has been described, with the result stated. When the stroke of the pump as adjusted by knob 54 is of medium length and the excess slippage of liquid is of average magnitude then such corrections may occur perhaps after every fifteenth stroke. For example, during fifteen strokes there may be escape of transmission liquid from chamber 19 but at the sixteenth stroke the vacuum created will be sufficient to overcome the pressure of the spring on the compensating valve 43 whereupon the liquid in chambers 19, 20 will be replenished from chamber 41.

This cycle of correcting actions may be repeated indefinitely except that a change of operating factors such as a drop or increase of the discharge head on the ultimate pump chamber 44 may tend to affect the slippage of transmission liquid and so to provoke the compensating action described after a greater or smaller number of strokes. During all this time the discharge of the pump is constant except for a perfectly negligible and practically immeasurable lag at the moment of each correcting or compensating action.

Should excess slippage occur on the suction stroke rather than on the pressure stroke then similar compensations occur through valve 42 whenever the amount of transmission fluid in chambers 19, 20 and 21 becomes sufficient to extend the diaphragm 26 into the pumping chamber 44 to such an extent that the valve disk 34 is seated on seat 35.

Assuming now that by operation of knob 54 and screw 52 the stroke of piston 15 is reduced in length then the pulsation of diaphragm 26

will shrink and the pump discharge will be less. Accordingly if excess slippage occurs on the pressure stroke it will take a greater number of pulsations to allow the suction stroke to reach a limit at which the control valve seats with consequent replenishment of transmission liquid through the proper compensation valve. However, the diaphragm will reach such a limit and the control parts are so dimensioned that the limit is reached before the diaphragm, during any part of its travel, abuts against any wall of the diaphragm chamber. Compensation will take place and will return the diaphragm pulsation to its proper limits. Thus the automatic compensation described is operative irrespective of the length of the piston stroke.

Both during a period of readjustment of the length of stroke as well as during operation with any length of stroke, the reciprocation of the mechanical piston and the consequent pulsation of the transmission fluid, and the pumping action of the diaphragm continues and the automatic volume compensation of transmission liquid is operative, the means provided for the same being independent from the adjusting means.

Fig. 10 should be considered for an understanding of how this machine differs from diaphragm pumps of the prior art, as to operation under normal or variable loads. The figure is a diagram of a typical device of the prior art. No claim is made for a device of such kind. The diaphragm 62 has ferric chloride on the righthand side thereof. It is exposed to the atmosphere on the lefthand side. At the center of the diaphragm an actuating rod 63 is attached thereto extending in direction normal to the diaphragm plane to the left. Rod 65 is reciprocated by link 64 driven by the crank 65 of a motor 66. The motion of the rod is mechanically imparted to the center of the diaphragm and is in some way reflected by a change of the volume of pump chamber 67 on the righthand side of the diaphragm, the tendency being for the center of the diaphragm to precede the outer portions thereof and for the outer portion to be warped in concave form 62X due to the liquid pressure on the righthand side. As this form is reversed twice during each stroke there is obviously much wear and tear on the diaphragm material, even if pusher plates of liberal size are attached and the diaphragm is molded so that it has some play. Furthermore no constant relation exists between the length of the stroke of rod 63 and the volumetric contraction or expansion of chamber 67. For instance as long as the level of ferric chloride in supply tank 60 is at 60B, a suction stroke from 62A to 62B causes the diaphragm to assume substantially the shape indicated at 62Y at the end of the stroke. Under such conditions a certain amount of ferric chloride, say for instance 1 cu. in. when using a particular size and construction of apparatus, may be displaced during each stroke. However, when the level of ferric chloride in supply tank 60 drops to 60C then an identical suction stroke from 62A to 62B causes the diaphragm to assume substantially the shape indicated at 62Z at the end of the stroke. Under such conditions the diaphragm is more concave on the left side thereof than at 62Y and the amount of ferric chloride pumped on each stroke is less than 1 cu. in. because the negative pressure of the ferric chloride acting on each of the several points of the diaphragm towards the righthand side thereof is greater and therefore more effective to balance the operating force

transmitted to such points from rod 63 which acts towards the lefthand side; said operating force being transmitted from rod 63 to each of said points by the flexible solid substance of the diaphragm itself. Similarly any change of the discharge head affects the rate of pumpage. Changes of suction or discharge load may be due to variation in operating conditions, or to structural changes. In some cases it may be possible to effect the change by an adjustment made in the mechanical parts moving rod 63. Frequently however, it is impossible and in all cases it is inconvenient to make such adjustment when gradual or sudden changes of pump loadings occur.

Fig. 3 sufficiently illustrates the action of the present device under similar conditions. Here the operating force is transmitted to each point of the diaphragm by liquid bearing against the lefthand side of the diaphragm, not by a rigid actuating rod and the flexible diaphragm material. Pressures acting on any point of the diaphragm are balanced at all times. The excessive motion and wear of the diaphragm center is eliminated. During a suction stroke the diaphragm tends to be convex rather than concave on the lefthand side thereof. Its precise shape is unaffected by the suction lift or discharge head, the feed is constant and the only reaction to varying loads is in the consumption of electric current in the prime mover, which is negligible.

The transmission liquid preferably is a non-congealing, non-conducting lubricant of little viscosity, such as a light oil. In that event the guide box 30 is automatically lubricated so that reciprocation of rod 27 absorbs a minimum of power, producing maximum accuracy of the diaphragm motion. The hydraulic transmission and control thereof will be operative under all conditions of service actually met with in practice. Ultimate failure of diaphragm 26, which cannot be altogether avoided in practice except when replacing the diaphragm in time, can be easily and automatically detected by means such as electric contact 80 extending into and insulated from diaphragm chamber 21 and connected to the positive pole of a source 82 of direct electric current, the negative pole being grounded to the metallic casting of chamber 21 through the coil of a relay 83 actuating an alarm device 84 or the like. A spark plug 81 is a convenient and economical means to provide the interior contact 80. Should diaphragm 26 develop any initial fatigue or crack there would be seepage and later leakage of ferric chloride through the diaphragm into chamber 21, adding to the electric conductivity of the liquid in said chamber. This would complete a circuit exciting the relay and operating the alarm. A safety switch in the circuit of motor 10 may be provided in operative connection with the detector relay. By such means the system can be fully protected against failure of mechanical parts, loss of ferric chloride, and destructive action of the same.

While I have described one embodiment of my invention, I wish it understood that various modifications can be applied all of which are intended to be covered by the following claims.

I claim:

1. A pump comprising a chamber, a flexible diaphragm dividing said chamber into two compartments, a liquid inlet into and an outlet from one of said compartments, a fluid displacing member in the second compartment, a partition in said second compartment interposed between said

diaphragm and said fluid displacing member, an opening in said partition and means for closing said opening upon movement of said diaphragm to predetermined positions.

2. A pump comprising a chamber, a flexible diaphragm within said chamber dividing the same into two compartments, suction and discharge conduit means communicating with one of said compartments and a cylinder communicating with the other of said compartments, a piston in said cylinder, means for operating said piston, a rigid partition in said second compartment interposed between said diaphragm and said piston, a passageway in said partition, a rod attached to said diaphragm and extending through said passageway, and means carried by said rod for closing said passageway upon movement of the diaphragm to predetermined positions.

3. In combination, a flexible diaphragm, a chamber sealed by said diaphragm and adapted to receive and hold a liquid bearing against said diaphragm, a liquid in said chamber, means associated with said chamber adapted to displace a volume of said liquid from one position to another position therein whereby said diaphragm is caused to pulsate, and means operable upon a predetermined movement of said diaphragm to seal said diaphragm from said liquid displacing means.

4. Apparatus according to claim 3 wherein said means controlled from said diaphragm comprises a restricted passageway interposed between said displacing means and said diaphragm, a valve associated with said passageway, and means movable with the motion of said diaphragm to open and close said valve.

5. In combination, a flexible diaphragm, a casing sealed at one end by the same, said casing being adapted to receive and to hold a liquid bearing against said diaphragm, a liquid in said casing, power driven means adapted to shift such liquid in said casing, a partition in said casing interposed between said diaphragm and said power driven means, said partition being provided with an opening for flow of said liquid therethrough, means associated with said opening in said partition providing a variable passage for the flow of said liquid therethrough toward and away from said diaphragm, and a second casing sealed by said diaphragm facing said first named casing and adapted to receive and discharge fluid to be pumped.

6. Apparatus according to claim 5 including automatic means for operating said means associated with said opening in said partition to control said variable passage, said means becoming effective to vary said passage when said diaphragm moves beyond a predetermined position.

7. Apparatus according to claim 5 including an auxiliary storage chamber for said liquid, said storage chamber having a common wall with said first casing, compensation valve means in said common wall, and means adapted to control operation of said compensation valve means to cause adjustment of the volume of such liquid in said first casing, such adjustment being caused by the pressure resulting from said power driven means.

8. Apparatus according to claim 5 including a means for indicating failure of said diaphragm comprising an electric circuit including a pair of terminals extending into said liquid and adapted to be joined to a source of electric current, and to be completed across said terminals upon mixture with the liquid in said power transmission chamber of an electrolytic liquid being pumped.

9. In combination, a chamber having a diaphragm in one end portion thereof, a movable displacement member in the other end portion thereof, means for moving said displacement member, a partition between said end portions, a passage in said partition, and means for limiting the motion of said diaphragm comprising means for closing said passage in response to certain positions of said diaphragm.

10. In combination, a chamber having a flexible diaphragm and a piston therein, a fluid in said chamber, said piston being adapted to displace said fluid to operate said diaphragm, and means controlled by said diaphragm and adapted to confine the motion of said diaphragm in predetermined limits comprising means to cut off from and to readmit to said diaphragm fluid pressure resulting from motion of said piston upon travel of said diaphragm to said limits.

11. Apparatus according to claim 10 including means to adjust the length of the stroke of said piston so as to thereby adjust the volume of the pulsation of said diaphragm, said adjusting means being independent from said diaphragm controlled means.

12. A pump comprising a motor, linkage driven by said motor, a piston driven by said linkage, a cylinder for said piston, an extension of said cylinder, a flexible diaphragm in said extension sealing the same, a chamber sealed by said flexible diaphragm and facing said extension, suction and discharge conduits joining said chamber, check valves in said conduits, a rigid diaphragm in said extension between said cylinder and said flexible diaphragm, a passageway in said rigid diaphragm having its axis normal to the plane of said flexible diaphragm, valve seats at the ends of said passageway, a rod secured to said flexible diaphragm and extending from the same through said passageway and held in position normal to the plane of said flexible diaphragm, a sleeve loosely riding on said rod, means to yieldably position said sleeve on said rod so that the sleeve may extend through said passageway, said sleeve clearing said passageway, valve disks secured to said sleeve and adapted to seat on said valve seats, compensating valves in said extension between said cylinder and said rigid diaphragm, and a chamber adapted to communicate with said extension through said compensating valves.

13. Apparatus according to claim 12 wherein the axis of said cylinder is vertical and that of said extension and passageway horizontal.

14. Apparatus according to claim 12 wherein said linkage is of the compound type, means being provided to adjust said linkage so as to control the length of stroke of said piston.

15. Pumping apparatus comprising in combination a casing, a flexible diaphragm dividing said casing into a pumping chamber and a power transmission chamber, a non-electrolytic power transmission liquid in said transmission chamber and bearing against said diaphragm, power driven means for pulsatingly actuating said liquid, and means for indicating failure of said diaphragm comprising an electric circuit adapted to be joined to a source of electric current, said circuit having a pair of terminals extending into said power transmission liquid, and adapted to be completed through the dilution of the power transmission liquid with an electrolytic liquid being pumped.

CERTIFICATE OF CORRECTION.

Patent No. 2,303,597.

December 1, 1942.

SAMUEL L. ADELSON.

It is hereby certified that error appears in the printed specification of the above numbered patent requiring correction as follows: Page 4, first column, lines 60 and 61; for "34R-34S to the line 34T-34U. In the place" read --26T-26U. This in turn tends to displace--; line 62, for "34-34S" read --34R-34S--; page 6, second column, line 28, for "pitson" read --piston--; and that the said Letters Patent should be read with this correction therein that the same may conform to the record of the case in the Patent Office.

Signed and sealed this 2nd day of February, A. D. 1943.

(Seal)

Henry Van Arsdale,
Acting Commissioner of Patents..
